ARRANGEMENTS FOR CARRYING OUT CONTINUOUS PROCESSES ON LONG RIGID ARTICLES

James Arthur Spencer, Northumberland Heath, Erith, England, assignor to British Insulated Callender's Cables Limited, London, England, a British company

Application November 17, 1951, Serial No. 256,946

Claims priority, application Great Britain
December 1, 1950

3 Claims. (Cl. 29—33)

This invention is concerned with conditions which arise in performing as a continuous process two operations in succession on a long sufficiently rigid article, for instance a tube, a rod, or some forms of electric cables, wherein each operation involves, or is accompanied by, the forwarding of the article along a line of travel. For instance the article may be fed from a source of supply to one piece of apparatus in which the first operation is performed, then passed from it to the second apparatus in which another operation is performed and then be withdrawn from the apparatus.

Owing particularly to the rigidity of the article under treatment it is important, in such cases, to secure close co-ordination of the two means for moving forward the article in order to avoid producing high stress in the article or interference with the performance of either or both of the two operations. It is not an easy matter to do this by simple observations and hand control since the rigidity of the article will prevent the disclosure of the existence of high stress until this becomes excessive and the interference with the performance of the operations may not become obvious until some defect has been produced.

It is pointed out that the required forwarding speeds on the two pieces of apparatus may not be the same, since one of the operations performed may have the effect of lengthening the workpiece. This occurs, for instance, where one of the operations is a drawing operation.

It is the object of the present invention to provide automatic means for securing the required co-ordination. In accordance with the invention one of the forwarding means, with any appropriate associated gear, is mounted on a carriage which is movable through a short distance in the line of travel of the article against a centralizing force. When this carriage is displaced from the central position in either sense it acts upon control gear which influences the speed of one of the forwarding means so as to adjust it in the sense required to produce correction of the condition which has caused the displacement. The displacement of the carriage is brought about by the force exerted on it by the rigid article being treated owing to the fact that it is being forwarded at different or non-coordinated speeds at different points in the length under treatment. For instance, if the forwarding means of the second operation in order of succession is causing the article to travel at a speed greater than that corresponding to the speed of the forwarding apparatus of the first operation, there is tension in the article between the two stages of treatment and this pulls the movable carriage away from its central position. This can be corrected by reducing the speed of the second forwarding means or increasing the speed of the first forwarding means.

Locking means for the movable carriage may be pro-

2

vided for dealing with temporary conditions such as occur at the starting up or near the end of the operations.

Gear associated with the forwarding means which it is appropriate to mount on the movable carriage with such means, may be gear which depends for its operation on the maintenance of a definite relationship with the forwarding means, which relationship would be disturbed by any abnormal relative displacement. The operation performed may include the forwarding movement as an inherent part for instance in drawing through a die, or the operation may be associated with the forwarding movement for the purpose of a continuous process, for instance in the making of a seam as by welding or soldering.

The movable carriage is preferably supported by suspension, the suspending members, two or more in number, being so formed as to offer sufficient transverse restraint to the carriage to avoid the necessity for lateral guides with their accompanying friction. The suspending members preferably also embody or consist of plate or strip springs cooperating to centralize the carriage and to permit small displacements longitudinally in either sense. Other forms of support may, however, be adopted, for instance a support similar to that above mentioned, but standing up from below instead of hanging down from above, or a table sliding or running on rolls in longitudinal guides with centralizing springs acting longitudinally in opposite directions.

One form of the improved apparatus is described hereinafter by way of example and with reference to the accompanying drawing, wherein:

Figures 1A and 1B together represent a view in elevation of the complete apparatus;

Figures 2A and 2B are respective plan views of Figures 1A and 1B;

Figure 3 is an end view of the apparatus as seen in the direction of the arrow III in Figure 1A;

Figure 4 is a view in elevation of the switch controlling the speed adjustment;

Figure 5 is a view of the arrangement shown in Figure 4, taken on the line V—V and as seen in the direction of the arrows; and

Figure 6 is a circuit diagram of the connections to the speed-controlling arrangements.

The apparatus is arranged to apply a sheath 1 of aluminum to a core 2 comprising an insulated cable conductor. The sheath 1 is formed from a flat strip 3 which is progressively folded about the core, the abutting longitudinal edges being welded together to form a tube 4 loose on the core 2 and the tube being subsequently drawn through a die 5 which reduces it to a tight fitting sheath on the core. The apparatus is in two distinct portions, namely, the tube-forming device which comprises the arrangements in Figure 1A excluding the die 5, and the drawing down device comprising the die 5 and the haul-off arrangements shown in Figure 1B. The first part forms the tube 4 from the strip 3 with the core 2 inserted as the tube is formed, and makes the seam; the second part reduces the diameter of the tube. In the course of the reduction of its diameter the length of the tube is correspondingly increased, so that the rate of travel of the finished article leaving the die 5 is greater than that of the strip and of the rate of seaming in the first part of the apparatus.

The movement of the tube 4 through the first part of the device is obtained by means of a double caterpillar haulage 6 electrically driven by an independent motor 7. The tube is drawn through the sinking die 5 in the second stage by means of a capstan 8 driven by an electric motor 9 through a variable speed gear 10. The control of speed is effected by means of this second drive, the variable gear 10 being adapted to be automatically

adjusted by a reversible auxiliary motor 11 controlled by switching arrangements described hereinafter.

The tube-forming device is supported on a carriage 12 suspended so as to be movable within pre-determined limits in the direction of movement of the strip 3 through the machine. The line of travel of the strip 3 from the commencement of its formation into the tube 4 to the contact between the finished cable 1 with the capstan 8 is a straight line. The distance between the delivery end of the caterpillar haulage 6 and the sinking die 5 is comparatively short and in this short space the work-piece has the form of a comparatively rigid seamed tube 4 which is a loose fit on the cable body 2 within it. It is in this space that the tube 4 may be subjected to forces of tension or compression as a result of relative variation in the haul-off speeds in the two parts of the machine. These forces are transmitted from the fixed sinking die 5 to the movable carriage 12, the latter being displaced in one direction or the other as a result. The rigidity of the tube 4 prevents the existence of undesirable tensile and compressive stresses from being observed until these stresses have reached values at which defects may arise, consequently manual control of the speed is extremely difficult if not impossible.

The carriage 12 comprises a long narrow horizontal frame, substantially rectangular as seen in plan, and consisting of two side members 13, 13 and a number of cross pieces 14. The forward portion of the frame is at a lower level than the rearward portion in order to accommodate the caterpillar haulage 6. The carriage 12 is suspended at each end and in a portal formed by two vertical pillars 15, 15 and a horizontal cross bar 16 at the top. In this portal is disposed a cross braced rectangular frame 17 conveniently formed of tubular members and constituting a link between two flat springs 18, 18 attached to the girder 16 and two similar flat springs 19, 19 attached to the back of the carriage 12. Each flat spring 18 or 19 is in the form of a plate having its plane disposed transversally to the direction of movement of the tube-forming strip 3. Each of the upper springs 18 is anchored in a bracket 20 by two bolts 21, 21 the bracket 20 being bolted to the cross piece 16. Each of the lower springs 19 is firmly attached to a vertical face 22 at the back of the carriage by two bolts 23, 23. Each spring is rigidly fastened to the link 17 by two bolts 24, 24. The breadth of the flat springs 18 and 19, the rigid construction of the link 17 and the rigid attachment of the springs 18, 19 to the carriage 12, to the upper cross piece 16 and to the link 17 are such that the carriage 12 is restrained more strongly against lateral movement than against longitudinal movement. At the same time the springs 18, 19 offer some resistance to the latter movement.

The following apparatus is mounted on the carriage 12. At the rearward end brackets 25 dependent from the carriage support a reel 26 carrying the strip 3 from which the tube 4 is to be formed. A set of three rolls 27 is adapted to receive the strip 3 passing upwards from the reel 26 to straighten it and set its position vertically on the carriage. From the straightening rolls the strip is passed between upper and lower forming rollers 28, 29, the lower 28 of which is grooved so that in its passage between them the strip is bent transversally into a U-shape, as indicated in Figure 3, the lower portion of its section being substantially semi-circular and the two sides extending upwards and outwards from this. The next apparatus carried by the carriage is a pair of guide rollers 30 freely rotatable about vertical axes and adapted to receive the U-shape strip between them from the forming rollers 28, 29. The strip 3 then passes through a circular die 31 which completes the bending of the strip into the circular form. Beyond the circular die 31 is mounted an arc welding torch 32 in co-operation with a pair of grooved pinching rollers 33, 33 rotatable on vertical axes and adapted to hold the abutting edges of the tube in

close contact during welding. Beyond the welding position the tube 4 passes through a self-centering guide 34. The insulated conductor is taken from any convenient source (not shown in the drawings) mounted independently of the carriage 12 and is directed into the groove (35 in Figure 2A) formed by the U-shape strip as it passes from the grooving rolls 28, 29 to the guide rolls 30. Between the grooving and guide rolls there is arranged a set of guides for the core 2, these guides being mounted on an independent fixed support 36 extending upwards between the sides of the carriage 12. The guides consist of two freely rotatable horizontal rollers 37, 38, and between them a pair of freely rotatable vertical rollers 39. The core is adapted to pass over the first horizontal roller 38, between the two vertical rollers 39, 39 and under the second horizontal roller 37.

The caterpillar haulage 6 comprises two endless belts 40, 40 each mounted in a carriage 41 supported in a frame 42. The carriers are attached by linkage to a hand wheel 43 whereby they may be moved towards and away from one another for the purpose of threading the leading end of the tube 4 between them. The caterpillars 40 are driven through gearing 44 from the motor 7 mounted on top of the frame 42. After leaving the caterpillar haulage 6 the pipe 4 passes into the sinking die 5, being lubricated by means of a suitable lubricating device 45. With the exception of the set of guides 37, 38, and 39 for the core 2 the whole of the apparatus of the first stage is displaceable with the carriage 12. For the purpose of anchoring the carriage 12 temporarily the pedestal 36 may carry a clamp adapted to co-operate with a suitable projection formed on the carriage and provided with a locking handle.

An insulating block 46 attached to a side member 13 of the carriage 12 carries a central contact 47 provided with a terminal 48 for attaching thereto a flexible load (the load 49 in Figure 6). Mounted on the floor adjacent to this contact 47 are two spaced brackets 50, 51, supporting between them two guide bars 52, 52 extending parallel with the direction of movement of the carriage. The guide bars 52, 52 support a block 53 of substantially rectangular section which is adapted to slide on the bars. An insulating plate 54 fixed to the top of the block 53 supports two spaced brackets 55, 55 carrying two contact blocks 56, 57 provided with suitable terminals 58, 59 for the attachment of flexible leads 60, 61 (Figure 6). These last mentioned contact blocks 56, and 57 are limit contacts and are disposed one on each side of the contact 47 which is fixed to the carriage 12. When the carriage is in its normal position, the block 53 is in the central position as shown in Figure 4. The central contact 47 is formed with a cylindrical surface and the contact surfaces on the limit contacts 56 and 57 are correspondingly recessed. Each bracket 50, 51 also supports an emergency limit switch 62 the operating lever 63 of which is adapted to be engaged by a vertical end face 64 of the block 53 when this is displaced towards its limiting position. The emergency limit switches 62, 62 are closed when not engaged by the block.

Referring now to the circuit diagram in Figure 6 there is shown a three-phase supply 65, 66, 67 adapted to be connected to the main motors, of which only the driving motor 9 for the capstan 8 is shown, by means of a main contactor 68. The hold-on coil 69 of this contactor is shown connected in series from one phase 67 through a normally closed stop switch 70, the two series-connected normally-closed limit switches 62, 62 and an auxiliary switch element 71 of the main contactor to another phase 65. The auxiliary switch 71 is short circuited by a connection 72 which includes a normally open push-button start switch 73. It will be seen that by closing the start switch 73 the coil 69 is energized, the main contactor 68 is closed and the start switch 73 is short circuited by the auxiliary switch 71 so that the contactor

coil 69 remains energized. The reversible gear-control motor 11 for adjusting the speed of the capstan 8 is connected to the three-phase supply 65, 66, 67 either by a reverse contactor 74 or a forward contactor 75. The forward contactor 75 is operated by a coil 76 connected to the power supply line 65 and to the fixed limit contact 56 which will be engaged by the central contact 47 if the carriage 12 is forced backwards due to the speed of the capstan 8 being too low. The engagement of these two contacts 47, 57 completes the circuit to the forward contactor coil 76 so that the contactor 75 closes and the motor 11 operates on the variable gear 10 to increase the speed of the capstan. When the limit contact 56 and central contact 47 separate with the return of the carriage 12 to its normal position the forward contactor coil 76 is de-energized and the motor 11 disconnected. The reverse contactor 74 is similarly operated by the engagement of the central contact 47 with the other limit contact 57 to close the circuit to the reverse contactor coil 77 when the carriage 12 is drawn forward as a result of the capstan 8 rotating too quickly. The reverse contactor 77 will open automatically when the carriage 12 returns to the normal position.

In the event of this automatic gear-changing device not operating as designed so that the undesirable tension or compression conditions are maintained, one of the emergency limit switches 62 will be automatically opened by the movement of the block 53. It will be seen from the circuit diagram that the opening of either of the emergency limit switches 62 will automatically deenergize the hold-on coil 69 of the main contactor 68 so that the whole apparatus will be brought automatically to a standstill.

In place of the caterpillar haulage 6 the movement of the tube 4 through the welding position may be obtained by two pairs of grooved driving rollers, engaging the tube before and behind the welding position. The automatic adjustment of speed may be carried out on the first or second drive, but it is preferred not to interfere with the speed of the tube through the welding position once this has been satisfactorily set. Also the speed adjustment may be effected through a motor-controller.

What I claim as my invention is:

1. In an arrangement for continuously processing a long rigid article moved along a line of travel through two successive process-stages by a separate forwarding device in each stage, automatic speed co-ordinating means for controlling the relative speeds of the forwarding devices, said speed co-ordinating means comprising a carriage for one of the forwarding devices, suspending members supporting the carriage from fixed supports, centralizing springs incorporated in the suspending members, the springs being adapted to centralize the carriage and the suspending members being adapted to permit displacement of the carriage from the central position in the said line of travel under the action of tension and compression forces set up in the article between the two stages against the centralizing springs, a speed regulator for one of said forwarding devices, and control means for said speed regulator, said control means being adapted

for operation by displacement of the carriage to adjust the speed regulator in the sense required to correct the condition which has caused the displacement.

5 2. In an arrangement for continuously processing a long rigid article moved along a line of travel through two successive process-stages by a separate forwarding device in each stage, automatic speed co-ordinating means for controlling the relative speeds of the forwarding devices, said speed co-ordinating means comprising a carriage for one of the forwarding devices, suspending members supporting the carriage from fixed supports, flat plate springs incorporated in the suspending members to centralize the carriage and to permit it to move through a short distance from a central position in the line of travel under the action of tension and compression forces set-up in the article between the two stages, the said plate springs being in planes transverse to the line of travel, non-flexible connections uniting the plate springs to the suspension members, to the carriage and to the said fixed supports, a speed regulator for one of said forwarding devices, and control means for said speed regulator, said control means being adapted for operation by displacement of the carriage to adjust the speed regulator in the sense required to correct the condition which has caused the displacement.

20 3. In an arrangement for continuously processing a long rigid article moved along a line of travel through two successive process-stages by a separate forwarding device in each stage, automatic speed co-ordinating means adapted to control the relative speeds of the forwarding devices, said speed co-ordinating means comprising a carriage for one of the forwarding devices, suspending members supporting the carriage from fixed supports, each of said fixed supports comprising a horizontal beam 30 and two uprights together constituting a portal within which the carriage is disposed, each suspending member being a rectangular cross-braced frame with a plate spring rigidly joined to each upper corner of the frame and to the horizontal beam and a plate spring rigidly joined to each lower corner of the frame and to the carriage, the suspending members and springs being adapted to permit displacement of the carriage from a central position in the line of travel under the action of tension and compression forces set up in the article between the two stages, a speed regulator for one of said forwarding devices, and control means for said speed regulator, said control means being adapted for operation by displacement of the carriage to adjust the speed regulator in the sense required to correct the condition which has caused the displacement.
